H. F. ROYSE.

BANANA STAND.

APPLICATION FILED DEO. 28, 1912.

1,078,804.

Patented Nov. 18, 1913.

UNITED STATES PATENT OFFICE.

HARVEY F. ROYSE, OF PERRYSVILLE, INDIANA.

BANANA-STAND.

1,078,804.

Specification of Letters Patent. Patented Nov. 18, 1913.

Application filed December 28, 1912. Serial No. 739,161.

To all whom it may concern:

Be it known that I, HARVEY F. ROYSE, citizen of the United States, residing at Perrysville, in the county of Vermilion and State of Indiana, have invented certain new and useful Improvements in Banana-Stands, of which the following is a specification.

My invention relates to new and useful improvements in display stands and the object of my invention is to provide a novel form of stand for supporting and displaying bananas, although the same may be used for displaying clothing or other articles desired.

A further object of my invention is to provide a display stand which will be extremely simple in construction and which may be positioned either from the floor or counter in the store or moved outside of the store to display the fruit and which is so arranged that it may be moved when the fruit is in place.

Heretofore it has been customary to display bananas by hanging the bunch from the ceiling or other suitable support by a rope, the fruit thus displayed being in the way and being continually jostled against and bruised with the result that it rapidly decays and all juice and waste from the fruit drips upon the floor and soils the same.

A further object of my invention is to provide a display stand which will protect the fruit from injury and which is provided with a drip pan adapted to receive all drippings therefrom.

With these and other objects in view, my invention will be more fully described, illustrated in the accompanying drawing, and then specifically pointed out in the claims which are attached to and form a part of this application.

In the drawing: Figure 1 is a perspective view of my improved display stand; Fig. 2 is a transverse sectional view taken at a point intermediate the two brace hoops and looking toward the bottom of the stand, this view being shown upon an enlarged scale; Fig. 3 is a fragmentary detail sectional view on the line 3-3 of Fig. 2.

Corresponding and like parts are referred to in the following description and indicated in all the views of the drawing by the same reference characters.

The preferred embodiment of my invention includes a rear supporting standard 10 and forward supporting standards 11 and 12, all symmetrically spaced from each other

with their lower ends bent outwardly to form supporting feet 13. The lower portions of the forward standards 11 and 12 are braced together and held in proper spaced relation by a brace 14, the ends of which are riveted or otherwise secured to the standards, as shown at 15. The supporting standard 10 is straight throughout its length with the exception of its foot, while the forward supporting standards 11 and 12 have their upper ends bent rearwardly and outwardly and then inwardly to engage against opposite portions of the rear standard 10 to which they are secured by rivets or other fastening devices 16, these curved portions being designated in the drawing by the numerals 17 and 18. The main body of the stand, thus formed, is further strengthened and braced by a pair of hoop sections 19 and 20, the ends of which are bent laterally as shown at 21 and secured to the rear faces of the forward standards 11 and 12 by rivets 22, while the intermediate portions of the hoop sections engage against the rear edge of the rear standard 10 and are bent inwardly upon either side thereof to surround the standard upon three sides as shown at 23, being secured in place by rivets 24. By this means, the display stand is properly stiffened and braced and at the same time the rearwardly curved arms 17 and 18 and hoop sections 19 and 20 form guards for the fruit or other articles supported by the stand. A hook 25 is provided with a laterally directed shank 90 having a downturned bifurcated portion 26, the members of which are positioned one upon either side of the upper end of the rear standard 10, bolts or rivets 27 being passed through said members and the standard to 95 firmly secure the hooked shank in place with the hook centrally disposed above the top of the stand. The bunch of bananas to be displayed may be suspended directly upon this hook by forcing the hook through the stem or may be suspended by a short cord, as preferred.

In order to provide means for catching all drippings from the fruit, I provide a drip pan 28, preferably formed of relatively light sheet metal and so shaped and proportioned that it may be readily passed between the forward standards and seated upon pins 29 extending from the inner faces of the standards 10, 11 and 12.

From the foregoing description, it will be apparent that I have constructed an ex-

tremely simple and effective form of stand for displaying bananas and one which may be employed with equal effect for the display of clothing or other goods for sale.

5 The entire stand will preferably be formed of metal and nickelated, japanned or otherwise finished to present a neat and attractive appearance, although, if desired, the stand may be formed of wood. In other words, I do 10 not wish to limit myself to any specific material or to the exact details of construction illustrated and described, as various minor changes within the scope of my claims, may be made at any time, without in the slightest 15 degree departing from the spirit of my invention. For instance, the standard 10 and hook 25 may be integrally formed, if desired.

Having thus described the invention, what is claimed as new is:

20 1. A display stand including a vertically disposed straight rear standard and a pair of vertically disposed forward standards, all of said standards being symmetrically spaced apart, the upper end portions of the forward standards being bent rearwardly and outwardly and then inwardly and secured by their free ends to opposite sides of the rear standard adjacent its upper end, hoop sections secured by their ends to the rear 25 faces of the forward standards and bearing by their intermediate portions against the rear edge of the rear standard, said hoop

sections being bent inwardly adjacent the rear standard to bear against the sides thereof, fastening devices passed through said 35 indent portions and through the rear standard, to secure the hoop sections in place, a drip pan mounted between the standards, and a forwardly directed hook carried by the upper end of the rear standard. 40

2. A display stand including a straight vertically disposed rear standard and a pair of vertically disposed forward standards, all of said standards being symmetrically spaced apart, hoop sections secured by their ends 45 to the forward standards and by their intermediate portions to the rear standards and lying in spaced horizontal planes, an inclined hoop section above the previously-mentioned hoop sections formed by bending 50 the upper end portions of the forward standards rearwardly and outwardly and then inwardly and securing same to the rear standard adjacent its upper end, and a forwardly directed hook carried by the upper end of the rear standard and extending in central position with respect to the three standards. 55

In testimony whereof I affix my signature in presence of two witnesses.

HARVEY F. ROYSE. [L.S.]
